UNITED STATES PATENT OFFICE.

JACQUES ROUSSO, OF CHICAGO, ILLINOIS.

TOWEL-CABINET.

1,157,046.

Specification of Letters Patent.

Patented Oct. 19, 1915.

Application filed January 12, 1912. Serial No. 670,776.

To all whom it may concern:

Be it known that I, JACQUES ROUSSO, a citizen of the United States, residing at Chicago, in the county of Cook and State of Illinois, have invented certain new and useful Improvements in Towel-Cabinets, of which the following is a specification.

The principal object of my invention is to provide a new and improved device for 10 supplying towels for public use.

Another object of my invention is to provide apparatus by which individual towels can be supplied successively to respective users.

15 These objects and others will be understood and appreciated, in connection with the following specification and claims, taken with the accompanying drawings.

In these drawings I have shown one specific embodiment of my invention, but the invention itself is defined in the appended claims.

I now proceed to describe this specific embodiment of my invention, and referring 25 to the drawings—Figure 1 is a perspective view of the apparatus in its normal condition. Fig. 2 is a similar view showing the cabinet opened up as it would be for the purpose of taking a towel out for use. Fig. 30 3 is a similar view showing a towel out in position for use. Fig. 4 is a vertical section. Fig. 5 is a detail sectional view showing a modification. Figs. 6 and 7 are perspective views of a detail element showing a towel 35 in its relation thereto. Fig. 8 is a perspective view of a locking rod. Fig. 9 is a perspective view of a latching element.

The apparatus comprises a box 15 to contain clean towels, standards 16 supporting 40 this box, an open receptacle 17 to receive soiled towels, and a rod 18 on which the towels are at all times strung. Above the box 15 for the clean towels is a mirror 19. The rod 18 has its upper end slightly reduced, as indicated by the reference numeral 20, and a screw threaded socket 21 is formed in this end of the rod 18. On the bottom 22 of the box 15 lies a removable 45 pallet 23 carrying an up-standing sleeve 24 securely supported by the inlaid plate 25. On the underside of the bottom wall 22 of the box 15 is attached a metal plate 26 with one end bent down and an eye 27 formed 50 therein. The rod 28 has an eye at its lower end designated 29 and its upper end screws into the socket 21. The padlock 30 engages

the two eyes 27 and 29 and thus holds the rod 28 from being unscrewed.

Each towel 32 has a gromet 31 around the edges of a hole in one side of the towel and 60 these gromets are strung on the sleeve 24, as shown in Fig. 4. Each towel is folded once, the free edge lying on top of the end carrying the gromet. This free edge of the upper towel is designated 33 in Fig. 4. 65

The box 15 has a cover 34 hinged at 35 and shown in open position in Fig. 4. The cover 34 is slotted to accommodate the rod 18, as indicated by the reference numeral 40.

The bottom wall of the soiled towel receptacle 17 is designated by the reference numeral 36. This has a hole 37 therethrough, one side of the hole being cut away above and below, as indicated in Fig. 4. The hole 37 is closed below by a plate 38. 70 75 The lower end of the rod 18 is bent forward, as indicated by the reference numeral 39, and in the normal relation of the parts this end 39 of the rod 18 hooks into the under cut-away space of the hole 37. 80

The alternative construction shown in Fig. 5 simply provides a hinge 41, the axis of this hinge being transverse so that the rod 18 can be rocked forward on this hinge without being lifted up. 85

In normal condition the parts will be assembled as shown in Figs. 1 and 4 with a considerable number, say fifty, of clean towels piled within the box 15 upon the pallet 23, all these towels being strung with 90 their gromets on the sleeve 24 that stands up from the pallet 23, and each towel being folded with its free end 33 uppermost. A person desiring to use a clean towel will step up in front of the apparatus in a position 95 facing the mirror 19 and with one hand will raise the cover 34 to the position shown in Fig. 2. The extent to which the cover can be raised is limited by the stop 42, so that when he lets go of this cover 34 it will fall 100 back to closed position by its own weight. The cover being raised by one hand, as just stated, the user of the apparatus will reach into the box 15 with his other hand and seize the free edge 33 of the uppermost towel, 105 drawing it up and forward. This will pull the said towel forward to the most forward part of the rod 18, the gromet 31 sliding along on the rod. Then the user will permit the cover 34 to drop back by its own 110 weight to closed position, the towel being in the position shown in Fig. 3 of the draw-

ings. While in this position the towel can be used either on the face or the hands, and finally when the user is through with it he lets go of it and it falls down into the receptacle 17, the gromet 31 all the time sliding along on the rod 18.

If several persons, say two or three persons, desire to use clean towels at the same time, they can do so, one of them standing a little at one side of a position directly in front of the apparatus, and another standing a little at the other side, each one using his individual towel at the same time as the other or others.

As the towels accumulate in the receptacle 17 they remain always strung with their gromets on the rod 18 and the parts being locked in place by the padlock 30, it is impossible for any person to steal any of the towels.

When it is desired to replenish the box 15 with clean towels, this is done by removing the padlock 30, unscrewing the rod 28 and pulling it down and out. Then the upper reduced end 20 of the rod 18 can be sprung up a little out of the sleeve 24 and then the rod 18 can be swung forward. This movement will swing the lower end 39 of the rod 18 back so that it can be lifted up out of the hole 37. Thereupon all the soiled towels in the receptacle 17 will fall off of the lower end of the rod 18 or can readily be pushed off by the hand and removed for cleaning them. At the same time the pallet 23 can be lifted out of the box 15. If desired several pallets 23 may be kept on hand, each one piled up with the proper number of clean towels, and when one is removed, another can be instantly put in its place. Or, if desired, clean towels can be piled up on the removed pallet and it can be put back in the box 15 in the position shown in the drawings.

After the pallet supplied with clean towels has been put back in the box 15, the lower end 39 of the rod 18 is stuck down in the hole 37, then the rod is pushed back and its upper end 30 sprung into the socket in the upper end of the sleeve 28. Then the rod 28 is screwed in place and locked by the padlock 30. This brings the apparatus to normal condition ready for use, as already described.

It will be observed that the socket 37 and the coacting end 39 of the rod 18 are so shaped as to prevent rotation of the rod 18 in said socket 37. This prevents swinging the forwardly projecting intermediate part of the rod 18 off to either side of its normal medial position. As an alternative construction the rod 18 may be hinged below, as indicated by 41 in Fig. 5, but in this case the soiled towels have to be removed by sliding them along the rod 18 and off the upper end thereof.

It will be seen that I have provided ap-

paratus by which a supply of clean towels can be kept on hand for instant use, that they may be withdrawn therefrom and used without inconvenience, and that at any stage they are retained by the apparatus and cannot be stolen.

The device as described may be supplemented by coin controlled mechanism, so that its use shall depend on the insertion of a coin in a slot. 75

I claim:

1. In a device of the class described, a towel support; and a retaining member extending upwardly from said support and then downwardly sufficiently to constitute a suitable guide for a towel while in use, substantially as described. 80

2. In a device of the class described, an elevated towel support; and a retaining member extending upwardly from said support and then downwardly sufficiently below said support to constitute a suitable guide for a towel while in use, substantially as described. 85

3. In a device of the class described, an elevated towel support; and a retaining member extending upwardly from said support and then downwardly sufficiently below said support, said retainer being provided below said support with a substantially vertical portion of considerable length to constitute a suitable guide for a towel while in use, substantially as described. 90

4. In a device of the class described, an elevated towel support; and a retaining member extending upwardly from said support, then outwardly and downwardly sufficiently below said support, then inclined rearwardly and downwardly under said support and then downwardly substantially vertically to constitute a suitable guide for a towel while in use, substantially as described. 100

5. In a device of the class described, a towel support; and a retaining member extending upwardly from adjacent the outer edge of said support and then downwardly sufficiently to constitute a suitable guide for a towel while in use, substantially as described. 110

6. In a device of the class described, a towel support; and a retaining member extending upwardly from adjacent the outer edge of said support, then outwardly and downwardly sufficiently below said support, then inclined rearwardly and downwardly under said support and then downwardly substantially vertically to constitute a suitable guide for a towel while in use, substantially as described. 120

7. In a device of the class described, a stationary support; a readily removable pallet resting on said support and adapted to serve as a carrier for perforated articles; and a retaining member extending upwardly 130

from said pallet then outwardly beyond and downwardly below said support and adapted to serve as a guide for perforated articles on said pallet, substantially as described.

- 5 8. In a device of the class described, a stationary support; a readily removable pallet resting on said support and adapted to serve as a carrier for perforated articles; and a retaining member extending upwardly 10 from said pallet, then outwardly beyond and downwardly below said support, said retainer being provided below said support with a substantially vertical portion of considerable length adapted to serve as a guide 15 for perforated articles on said pallet, substantially as described.

9. In a device of the class described, a frame, a shelf supported thereby, a pallet resting on said shelf, and a rod connected to 20 the pallet and extending upwardly therefrom, then forward and then down past the front edge of said shelf, said rod having a detachable joint at a point in the portion thereof that extends up from the pallet.

- 25 10. In a device of the class described, a frame, a box carried thereby, a rod having one end attached to the bottom of the box within the same near its front and extending thence up then forward then down past the 30 front of the box and back beneath the box, a hinged cover for said box having a notch in its forward edge to accommodate the said rod, and a receptacle underneath the box, the lower end of said rod extending into said 35 receptacle and fastened to the bottom thereof.

11. In a device of the class described, two rectangular boxes supported one above the other, a removable pallet within the upper 40 box, a rod having one end carried by said removable pallet and extending upwardly therefrom, thence forward, down and under the upper box and into the lower box, said rod being jointed at a point directly above 45 its connection with said pallet.

12. In a device of the class described, a clean towel and a soiled towel box, a removable pallet within the clean towel box, a rod

extending upwardly from the upper side of said pallet and thence to the soiled towel 50 box, said rod consisting of a tubular standard with its lower end fixed on said pallet, a solid portion jointed to the upper end of said tubular standard and extending therefrom to the soiled towel box, and a fastening 55 rod extending through the bottom of the clean towel box and through said tubular standard engaging the proximate end of the solid portion of the rod.

13. A towel dispenser comprising an upright support, a bracket mounted on said support and adapted to support a pile of towels placed one above another thereon, a locking device carried by said bracket, a rod having a goose-neck formed on its upper 60 end and adapted to engage said locking device, a loose towel-carrying sleeve adapted to telescope with the end of said rod and pass loosely through eyelet holes in a series of towels to facilitate the placing of the 65 towels on said rod, said sleeve normally resting on the support for said towels, the towels slipping off the upper end of said sleeve as they are lifted from the top of the pile on the shelf, and a hamper provided beneath 70 said bracket and into which the lower end 75 of said rod extends.

14. A towel dispenser comprising a support, a towel-supporting shelf mounted thereon, a locking device mounted on said 80 shelf, a rod having a goose-neck terminating in a downwardly projecting end that is adapted to overhang said shelf and engage said locking device, the other end of said rod being inclined inwardly and downwardly 85 from said goose-neck, and a hamper having an open top wherein the lower end of the downwardly and inwardly inclined portion of said rod is secured.

In testimony whereof, I have subscribed 90 my name.

JACQUES ROUSSO.
